Primary Examiner — Mitchell Siegel(74) Attorney, Agent, or Firm — Banner & Witcoff, Ltd.(57) CLAIM

The ornamental design for a golf club head, as shown and described.

DESCRIPTION

FIG. 1 is a first perspective view of a golf club head showing our new design;

FIG. 2 is a bottom view thereof; and,

FIG. 3 is a second perspective view thereof.

The broken lines immediately adjacent to the shaded area represent unclaimed boundaries of the design. The broken lines showing the remainder of the golf club head are for environmental purposes only and form no part of the claimed design.
